Patented Aug. 4, 1914.

UNITED STATES PATENT OFFICE.

JAMES E. M. BROOKE, OF WASHINGTON, DISTRICT OF COLUMBIA, ASSIGNOR OF ONE-HALF TO HADLEY Y. BROOKE, OF LUVERNE, ALABAMA.

PRINTER'S GALLEY.

1,105,957.

Specification of Letters Patent.

Patented Aug. 4, 1914.

Application filed June 12, 1913. Serial No. 773,225.

To all whom it may concern:

Be it known that I, JAMES E. M. BROOKE, a citizen of the United States, and resident of Washington, in the District of Columbia, have invented certain new and useful Improvements in Printers' Galleries, of which the following is a specification.

While my invention is designed to handle the type set on the monotype machine, it is, of course, obvious that any form of type may be set in it, including the linotype.

The present system of handling type is slow, expensive and at all times hazardous. All short "takes" set must be carried by the "casterman" from one room to another, and there it is handled again by the "bankman." All the long "takes" have to be brought in to the same man, the matter shifted from one side of the galley to the other, another galley placed, and in every instance must be shifted.

The object of my invention is to provide a type galley that will handle all type handled by the galley now in use, but will handle the monotype product as well, doing away with all handling or shifting of matter by means of a detachable head-piece; also greatly facilitating the make-up, as it will do away with the lifting of matter; and with these and other objects in view, my invention consists of the parts and combination of parts as will be hereinafter pointed out.

In the drawing:—Figure 1 is a perspective view of a galley embodying my invention; Fig. 2 is a perspective view of a galley embodying my invention with the detachable head detached; Fig. 3 is a longitudinal vertical section of the galley, the head being removed; Fig. 4 is a transverse sectional view of the galley looking in the direction of the head; Fig. 5 is a detail sectional view.

The reference numeral 1 designates the bottom of my improved galley, and 2 the side members thereof. Each side member is provided in its inner face with a double L-shaped slot 3 near one end and a vertically disposed elongated slot 4 near its other end, the elongated slot of one side being directly opposite the lower portion of the double L-shaped slot of the other side, said double L-shaped slot extending at its lower end to the plane of the bottom 1 of the galley, while the slot 4 is positioned substantially midway between the top and bottom of the side mem-

bers 2, as better seen in Fig. 2. The wall of the lower portion of the double L-shaped slot and of the elongated slot constitute abutments for the head of the galley.

The detachable head 5 is of a length equal to the distance between the side members between which it extends. This detachable head is provided on one end with a lug 6 extending in the direction of its length and positioned about midway between the top and bottom of the head; said head being provided on its other end with a lug 7, the bottom line of which is in the plane of the bottom of the head as seen in Fig. 3, whereby it may rest in the bottom portion of the double L-shaped slot 3 when the head is in operative position in the galley.

In assembling the parts, the lug 6 is inserted into the groove or elongated socket 4 whereupon the lug 7 is placed in the upper portion of the groove 3 and pressed downward in said groove, thence forward and thence downward in the bottom portion of the groove until it is seated on the bottom of the groove when the bottom of the head is snug on the bottom 1 of the galley. The elongated groove 4 is always on the "type side" of the galley when the head is in position. When the head 5 is locked in position in the galley, it is impossible to displace it accidentally, nor can the weight of the type set in the galley displace it as the walls of the two grooves constitute abutments for the head beyond which it cannot move except when intentionally manipulated. After matter is set up in this improved galley, it can be removed therefrom by removing the head 5 joining the galleys and sliding the matter at will from one galley to another.

Another good feature of my improved galley is that the head is always in place, giving it the same appearance of the present form of galley.

It frequently occurs in book offices that they have to get out pasters or large tables which require a great deal of care and extra hard work for the "make-up," consuming considerable time. My improved galley will eliminate trouble of this character, inasmuch as the head piece may be readily removed and the matter slid from one galley to another in perfect safety.

Of course, it will be understood that the head piece may be used with equal efficiency at either end of the galley.

I claim:—

A printer's galley having a double L-shaped slot in the inner face of each side member, the lower portion of each of which 5 extends to the plane of the bottom of the galley, and a vertically disposed elongated slot in the inner face of each side member of the galley disposed directly opposite the lower portion of the double L-shaped slot, and a detachable head piece adapted to fit 10 bodily between the side members and having a lug extending axially from one end midway of the height of the head, and con-

structed to engage the vertical slot, and a lug extending axially from the other end of the 15 head disposed at the bottom thereof and adapted to engage the lower portion of the double L-shaped slot when the head is in locked position.

In testimony whereof I affix my signature 20 in presence of two witnesses.

JAMES E. M. BROOKE.
